UNITED STATES PATENT OFFICE.

HENRY M. RUSSELL, JR., OF WHEELING, WEST VIRGINIA.

DRINKING-CUP.

1,081,468.

Specification of Letters Patent. Patented Dec. 16, 1913.

Application filed October 21, 1912. Serial No. 726,905.

To all whom it may concern:

Be it known that I, HENRY M. RUSSELL, Jr., a citizen of the United States of America, residing at Wheeling, in the county of Ohio and State of West Virginia, have invented a new and useful Improvement in Drinking-Cups, of which the following is a description.

One object of my invention is to provide 10 a drinking cup which shall be of a convenient size for use but which may be folded into a very small space.

Another object of my invention is to provide 15 a cup which when folded shall be little liable to injury.

Another object of my invention is to provide 20 a cup of simple construction and one that may be easily cleaned and easily manufactured.

25 My invention consists of a number of thin strips of metal or other suitable substance held together loosely at their ends by rivets or other connectors so that when not under tension they form a flat pack. The strips are so shaped, however, and the holes, 30 through which the rivets or other connectors pass, are so placed that the strips or leaves may be bent into a half ring and then spread out to form a cup shaped much like half a melon.

Referring now to the drawings forming a part hereof Figure 1 is a top view of the cup folded. Fig. 2 is a side view of the cup folded. Fig. 3 is an end view of the cup 35 extended. Fig. 4 is a top view of the cup extended, and Fig. 5 is a detail view herein after described.

In Fig. 2 single lines were used to represent the edges of the blades because in the 40 actual cup from which the drawings were made the thickness of the leaves was less than the width of the lines used. To show the edges with a light and a heavy line would give a wrong impression of the structure.

45 In all the figures the numeral 6 designates the leaves or blades of which the cup is made up and the numeral 7 designates the rivets or other connectors that hold the leaves together.

50 The numeral 8 designates a hole in a leaf 6.

Fig. 5 shows one end of a leaf 6 and the hole 8 which the leaf 6 has in it near its end and also one of the rivets or other connectors 55 7, the head of which has been removed to show the hole 8 and the relation thereto of the shank of the rivet or other connector.

When folded the cup is merely a flat pack 60 of thin strips held together loosely by two rivets. As will be seen by reference to Fig. 2 the rivets or other connectors 7 have shanks longer than the aggregate thickness of all the leaves. This allows the ends of the leaves to separate slightly when they are 65 extended and gives them a twist that tends to keep them in contact. It is not necessary to have the shanks of the rivets or other connectors as long as they are shown in the drawing. I prefer considerable excess of 70 length in the shanks but it is only necessary to have such excess as will insure that the blades will be free to move with respect to each other. The hole 8 must be somewhat 75 larger than the shank of the rivet or other connector 7 so as to allow the latter some play. Otherwise it would be impossible to spread the leaves. It is immaterial whether the connectors be rivets or whether they have one or both heads screwed on or 80 whether their form is like that shown. They might have any one of a number of forms unlike that shown without departing from the spirit of the invention. The leaves also might be given a variety of shapes without 85 departing from the spirit of the invention.

The leaves are preferably so shaped and the holes are preferably so located that one edge of each leaf is less curved than the other edge and that the holes are nearer to the 90 more curved edge than to the less curved edge but that the center of a straight line joining the two holes in any leaf will be nearer to the less curved edge than to the more curved edge. This insures that when 95 the leaves are sprung and spread out one shall overlap another. It also tends to keep them in contact. The leaves make such angles with each other that outside each line of contact there is a narrow V shaped 100 trough. The surface tension of the liquid in this trough, when any liquid has leaked through, tends to prevent further leakage.

The word "elastic" as applied herein to

the leaves of the cup, means having a tendency to straighten out when bent—like a watch-spring. It does not mean that the leaves may be stretched out and will contract 5 like a rubber band.

I claim:

1. In a drinking cup the combination of a plurality of thin flat narrow leaves each leaf having a hole in it near each end, said 10 holes being so placed that the middle point of a line joining them will be unequally distant from the edges of such leaf, two connecting members holding the leaves together, one of said connecting members passing 15 through one hole and the other of said connecting members passing through the other hole in each leaf.

2. In a drinking cup a plurality of flat narrow elastic leaves a hole near each end 20 of each leaf and two suitable connectors, one passing through one hole of each leaf, the said holes being of such size and shape with respect to said connectors that the latter shall have lateral play in at least one 25 direction in said holes.

3. A drinking cup comprising a pack of flat leaves so shaped that they may be sprung in either of two directions and then spread out into a cup shape, and connectors 30 adapted to hold said leaves together in either the pack or the cup form and to permit the change from one form to the other.

4. In a drinking cup the combination of a plurality of thin flat elastic leaves, rivets 35 connecting the ends of said leaves, said leaves being so shaped that they may be sprung into a substantially semicircular pack and then spread out to form a cup and that when so spread out they shall remain 40 extended.

5. In a drinking cup a plurality of flat leaves adapted to form a flat pack when not under tension or to be bent and spread 45 into cup form and to remain in such form under tension.

6. In a drinking cup the combination of two rivets and a plurality of elastic leaves of equal length, each leaf extending from one to the other rivet by a curve in a different 50 plane from that of each other leaf, and one edge of every leaf but one pressing against the inside surface of the next leaf.

7. In a drinking cup the combination of two connectors and a plurality of elastic 55 leaves, one end of each leaf being held by one of said connectors and each of said leaves being sprung so that its end portions shall be substantially parallel, said leaves being so disposed with respect to each other 60 as to form an approximately semi-ellipsoidal cup.

8. In a drinking cup the combination of two connectors and a plurality of thin elastic leaves, each leaf being curved on one edge

and straight on the other, and being held 65 by one of said connectors at each end, each of said leaves being sprung into a half ring, the said leaves being so disposed with respect to each other and so held that they shall form a cup and shall be kept in contact with each other by their own elasticity. 70

9. In a drinking cup the combination of a plurality of flat elastic similarly shaped leaves, each leaf being straight on one edge and so curved on the other edge as to be 75 widest at its middle point and having in it two holes, one near each end, said holes being nearer the curved than the straight edge of said leaf, but so placed that a line joining said holes will be nearer the straight 80 than the curved edge of said leaf at its widest point, and suitable connectors passing through said holes in such a way as to normally hold said leaves in a loose flat pack. 85

10. In a drinking cup the combination of two rivets and a plurality of flat elastic strips extending from one rivet to the other by such curves that each strip will be substantially tangent to a sphere at the poles of 90 which will be the said rivets, the respective lines of tangency being meridians on one hemisphere thereof, and adjacent leaves being in contact throughout substantially their entire lengths. 95

11. In a drinking cup the combination of two connectors and a plurality of elastic leaves, each leaf being held by one of said connectors at each end and each leaf being sprung into approximately a half ring, the 100 edge of each leaf but one pressing against the inside surface of the adjacent leaf so as to give a slight twist to each leaf.

12. In a drinking cup the combination of two rivets and a plurality of elastic leaves 105 of similar shape, each leaf having two holes in it, one near each extremity, one of said rivets passing through one of said holes in each leaf, said leaves being so shaped that the center of one edge of each leaf shall be 110 farther from said rivets than the center of the other edge, and each of said leaves but one overlapping an adjacent leaf.

13. In a drinking cup the combination of two rivets and a plurality of elastic leaves 115 having holes near their extremities and each sprung into a half ring and each held by one of said rivets at each end, said rivets passing through said holes and said rivets being long enough to allow the end portions 120 of said leaves to be separated from each other at one side.

14. In a drinking cup a number of members made of thin sheet material the edges of some of said members pressing against the 125 surfaces of other of said members but the interior angle at every such line of contact being greater than the exterior angle.

15. In a drinking cup the combination of a plurality of thin elastic leaves, each having two holes in it, one near each end and each leaf so shaped that the middle point of a line joining such holes shall be nearer to one edge of said leaf than to the other, the edge to which such point is nearer being substantially straight and suitable connec- tors passing through said holes and having some lateral play therein holding said leaves together.
